UNITED STATES PATENT OFFICE

ROSCOE D. CONKLIN, OF RAHWAY, NEW JERSEY, ASSIGNOR TO NATIONAL PNEUMATIC COMPANY, OF NEW YORK, N. Y., A CORPORATION OF WEST VIRGINIA

MECHANISM FOR REVERSING MOTIVE DEVICES FOR OPERATING DOORS AND THE LIKE

Original application filed June 7, 1929, Serial No. 369,205, now Patent No. 1,828,860, dated October 27, 1931.

Divided and this application filed May 24, 1930. Serial No. 455,284.

This invention relates in general to apparatus for use in conjunction with motive devices for operating doors, gates and the like by means of which the motive devices and the doors are reversed in direction of movement when they strike an object in their path.

One of the objects of this invention is the provision of relatively simple mechanism of the above nature for use in connection with movable doors and their operating mechanism which is simple and rugged in construction and adapted to easy and rapid manufacture and easy repair and replacement.

A further object of this invention is the provision of reversing mechanism for use in connection with all types of door operating motors, such as the pneumatic and electrical types.

A further object of the invention is the provision of a switch cooperating with the connecting mechanism between the motive device and the door which is arranged to be closed upon the door striking an obstruction to effect a reversal in movement of the operating mechanism.

These and other objects as will appear from the following disclosure are successfully attained by means of this invention.

This invention resides substantially in the combination, construction, arrangement and relative location of parts, all as will be set forth in detail in the following specification.

This application is a division of my co-pending application Serial No. 369,205, filed June 7, 1929.

Referring to the drawings which have been given in an illustrative sense—

Figure 1 is a side elevational view of one form of device for accomplishing the purposes of this invention;

Fig. 2 is a cross-sectional view taken on the line 2—2 of Fig. 1;

Fig. 3 is a side elevational view of a modified form of device for accomplishing the same results;

Fig. 4 is an elevational view of another form of the device as applied to the connecting link to be employed between the motive device and the door;

Fig. 5 is another view of the mechanism of

Fig. 4 with many parts broken away showing the switch construction and a part of the mechanism for operating it, which part is shown on the line 5—5 of Fig. 4; and

Fig. 6 is a diagrammatic association of the elements comprising this invention.

The most generally known and used form of reversing mechanism for power operated doors, gates and the like employs a flexible or collapsible shoe on the forward edge of the moving door which is deformed or collapsed when the door strikes an object so as to close a switch or similar controlling device connected to the motive device for operating the door to effect a reversal in movement thereof. The present invention has to do with several forms of devices by means of which similar results are secured without the necessity of employing a flexible or collapsible shoe on the forward edge of the door. To fully understand the structure of this invention reference will now be made to the drawings.

Referring to Fig. 1, the form of device disclosed therein comprises a pneumatic motor, shown generally at 1, of the differential type.

At this point it might be emphasized that the principles of this invention are not restricted to the form of motive device, whether it be pneumatic or electric, and the disclosure in the drawings is only given to illustrate the principles of the invention.

The pneumatic motor 1 is shown comprising a large and a small cylinder 2 and 3 and the piston rod 4 extending beyond the end of the smaller cylinder.

The pneumatic motor 1 is mounted on a base plate 5 which in turn is supported by a supporting plate 6 extending through a portion of the length thereof on each side, the flanges 7 comprising a vertical and horizontal portion.

These flanges enclose the edges of the base plate 5 in a manner so that the base plate and motor supported thereon may slide longitudinally of the supporting plate 6 guided by the flanges 7. Supported on one end of the base plate 5 is a bracket 8 to

which is secured the vertical arm 9 and the horizontal pin 10. The free end of the pin 10 extends through the bracket 12 secured to the supporting plate 6. The pin 10 is encircled by means of a heavy spring 11 which

lies between the bracket 12 and the arm 9. Secured to the upper end of arm 9 is a pin 13 having a reduced portion 14 on which is slidably mounted a contact disc 17 supported between the insulating members 16 and by means of which the disc is insulated from the portion 14. A spring 15 is mounted between the insulating members 16 and the contact disc 17 which are arranged to slidably move as a unit on the reduced portion 14 against the action of the spring 15 and the shoulder on the pin 13. Supported on a bracket 19 is a block of insulating material 18 which in turn supports the fixed contacts 20 which are arranged to be bridged by the contact disc 17. The piston rod 4 is, of course, intended to be connected by any suitable connecting link to the doors and the like to be operated by the motive device. The supporting plate 6 is provided with a stop pin 22 against which the base plate 5 is forced by means of the heavy spring 11 reacting on the fixed bracket 12. The pipe 21 is provided for supplying fluid pressure to the larger cylinder 2 of the motor 1. The operation of the device will be described later in connection with Fig. 6.

The modified form of device shown in Fig. 3 comprises, as before, the pneumatic motor 1 having the piston rod 4. Pivotedly secured to the piston rod 4 by the arms 26 of the connecting member 25 is a short shaft 27 which threadedly engages the connecting member 25 and is held in adjusted position by means of the lock nut 28. Two lock nuts 29 are also mounted on the shaft 27 against which presses the hollow sleeve 30. The end of the shaft 27 is provided with an enlarged portion 31 which acts as a stop for the plate 33 which encircles the shaft 27 and is forced against the portion 31 by means of the spring 32. The shaft 27 is provided with a reduced cylindrical portion 40 on which is slidably mounted and from which is insulated the contact disc 17. A spring 41 resiliently resists movement of the contact disc 17. A framework 34 is secured to the plate 33 and has supported thereon and insulated therefrom the contacts 20 adapted to be bridged by the contact disc 17. A shaft 35 threadedly engages the framework 34 and is held in adjusted position by means of the lock nut 36. The shaft 35 is adapted to be secured to the doors which are to be operated. The operation of this device will be described in connection with Fig. 6.

Another form of the device is shown in Figs. 4 and 5. The reversing switch in this case, as in the case of the form shown in Fig. 3, comprises a portion of the connecting link to be inserted between the motive device and the door. As before, the connecting member 25 is provided with the arms 26 which are to be pivotally connected to the piston rod of the motive device. A shaft 45 threadedly engages the connecting member 25 and is held

in adjusted position by the lock nut 46. A block 48 is adjustably secured to the shaft 45 and held in place by means of the lock nut 47. This block is provided with a cylindrical recess and an elongated slot extending therethrough at right angles to the recess, as shown at 49. A shaft 50 having a reduced portion fits into the recess in the block 48 and is provided with a pin 51 which lies in the elongated slot 49. Secured to the shaft 50 is another block 53 which is held in place by means of the lock nut 54. A heavy spring lies between the blocks 48 and 53. The other end of shaft 50 is provided with the connecting member 55 which is held in place by means of the lock nut 56 and is adapted to connect the mechanism to the door to be operated. Pivotally supported on the block 53 is an arm 57 which is provided at its outer end with a pair of rollers 59 and a downward projection 60. A spring 58 forces the arm 57 upwardly so that the rollers 59 engage the cam surface 61 of the block 48. Adjacent this mechanism is a supporting plate 62 on which are secured the spaced brackets 63 in which is mounted a shaft 64 for pivotally supporting the plate 66. As shown in Fig. 5 the plate 66 is urged upwardly by means of a spring 71 against the fixed stop 65. The plate 66 is provided with the extension 67 on which is secured the short pin 72 for slidably supporting the contact disc 17 which is insulated therefrom. The spring 73 resiliently resists movement of the contact disc 17. Also secured to the supporting plate 62 is a block of insulating material 70 to which is secured the spaced contacts 20 bridged by the contact disc 17. The operation of this form of the device will be described in connection with Fig. 6.

The diagrammatic showing in Fig. 6 illustrates the association of the elements of this invention. A wire 89 extends in the positive side of the current source to the push button switch 80. One terminal of this switch is connected by wires 81 and 82 to one terminal of the electro-magnetically operated fluid pressure valve 83. This fluid pressure valve is of a well known type extensively used in this art and when energized operates to permit the admission of fluid pressure through the pipe 84 and pipe 21 into the largest cylinder of the motive device 1. The other terminal of the winding of this valve is grounded as at 84'. Wire 81 also connects to one contact 20 and the other contact 20 is connected to wire 85. At 86 is shown diagrammatically a switch adapted to be mounted in the path of the door so as to be moved into the position shown in the figure just as the door closes so that the conducting strip 87 thereon moves out between the fixed contacts, one of which is connected to wire 85. The other fixed contact is connected by wire 88 to wire 89.

For sake of clarity, although it is well known in the art, it may be pointed out that the differential type of motor as shown here is always supplied in the smaller cylinder with fluid pressure. When fluid pressure is supplied to the larger cylinder the force exerted in the smaller cylinder is overcome and the motor operates to open the doors. To supply this fluid pressure to the larger cylinder the magnet valve 83 when energized connects the larger cylinder to the fluid pressure source through itself and the pipes 21 and 84. Thus to fully open the doors switch 80 must be held closed and kept closed in order to maintain the doors opened. As soon as switch 80 is opened magnet valve 83 becomes deenergized and permits the fluid pressure in the larger cylinder to exhaust to the atmosphere through the valve. The force exerted in the smaller cylinder then acts to close the doors. With this general discussion it is believed that the operation of the device, as now described, will be more fully understood.

25 In the arrangement shown in Fig. 1 when fluid pressure is supplied to the larger cylinder through the pipe 21 piston rod 4 begins to move to the right and carries with it the door which is connected thereto. The strength of spring 11 is such that it is able to resist all the normal reactions caused by the operation of the door and hence the motor 1, which is slidably supported on the supporting plate 6, does not move. As soon, however, as the door strikes an obstruction the motor tending to move the door on being unsuccessful will move to the left in Fig. 1 sliding on the supporting plate 6 and compressing spring 11.

40 The motor will continue to move carrying the arm 9 with it until the lower end of the arm strikes the fixed bracket 12. By this time contact disc 17 will have bridged the fixed contacts 20. As soon as the obstruction is removed spring 11 is strong enough to force the motor back so that the plate 5 strikes the stop 22 and the door continues to close until fully closed. The motor will, of course, continue to exert a force so that the motor will again move to the left until stopped by compressing spring 11. Contacts 20 will again be bridged but produce no reversing action since just as the door completes its closing stroke and before contact 17 bridges contacts 20 the switch 86 (Fig. 6) will have been moved by the door so that contact 87 moves out from between the fixed contacts breaking the circuit which includes the contacts 20. This operation will be described a little more in detail in connection with Fig. 6. To open the doors switch 80 is closed. Current then flows through wire 89, switch 80, wire 81, wire 82 through the magnet valve and wire 84' to ground. The magnet valve is energized to permit the delivery of fluid pres-

sure to the larger cylinder of the motor 1. The door then begins to open and continues to open to fully opened position and remains opened as long as switch 80 is closed. As soon as switch 80 is opened the larger cylinder of motor 1 opens to exhaust and the door begins to close. Should it strike an obstruction contact disc 17 will bridge contacts 20 as described above and current will flow through wire 89, wire 88, contact 87, wire 85, contact 20, contact disc 17, contact 20, wire 81, wire 82, magnet valve 83 and to ground at 84'. The door will then begin to open and continue to open until the obstruction is removed. It might be pointed out here that switch 86, of course, moves as soon as the door begins to open to a position where contact 87 bridges the fixed contacts.

The mechanism in Fig. 3 is, as illustrated, interposed between the piston rod 4 and the door. Thus during closing should the door strike an obstruction it is held against movement and with it rod 35 and bracket 34. The motor continuing to operate forces shaft 27 to the right against the action of spring 32 until contact disc 17 bridges contacts 20 when the circuits will be completed as before to reverse the direction of movement of the motor. As before, spring 32 which corresponds to spring 11 in the arrangement of Fig. 1 is of sufficient strength to prevent relative movement between shaft 27 and bracket 34 under normal operating conditions. In this form of mechanism, as in the first one described, a door switch 86 is of course employed. With the arrangement of Fig. 3, the wires connecting the contacts 20 must, of course, be flexible leads since this part of the mechanism must move backwards and forwards. The arrangement in Fig. 1 of course does not require flexible leads nor does the arrangement shown in Figs. 4 and 5.

The arrangement in Figs. 4 and 5 operates as follows: The mechanism of Fig. 4 is connected between the piston rod of the motor and the door to be operated. As the door closes spring 52 is strong enough to prevent relative movement between blocks 48 and 53. When the door strikes an obstruction, however, it as well as block 53 and the mechanism connected thereto, is held against movement. Since the motor continues to tend to move forward it will overcome the resistance of spring 52 and block 48 will be moved to the right. Its cam surface 61 acting on the rollers 59 will cause arm 57 to move downwardly so that the projection 60 strikes the plate 66. This causes plate 66 to move downwardly (Fig. 5) carrying with it arm 67, pin 72 and contact disc 17 to a point where the contact disc bridges the fixed contacts 20. Circuits are then complete, as described before, to reverse the direction of movement of the motor. In this form of device the door switch 86 may be eliminated because when the door is com-

pletely closed the link which connects it, as shown in Fig. 4, with the motor is moved sufficiently to the right so that the projection 60 of arm 57 has passed the rounded end 68 of plate 66. Thus, even though the arm 57 is moved downwardly as block 48 moves towards block 53, the door being closed, it does not act upon plate 66 and hence contacts 20 are not bridged. During the opening movement of 10 the door the end of plate 66 is turned downwardly, as shown at 68, so that the end 60 of the arm 57 may pass the end of the plate without striking it.

From the foregoing disclosure it will be 15 apparent that I have disclosed an exceedingly simple and yet rugged and efficient mechanism for carrying out the principles of this invention which employs certain principles of construction and operation. I am, of course, aware that these principles may be embodied in other forms of the device and I do not, therefore, desire to be strictly limited to the disclosure as given for purposes of illustration but rather to the scope of the invention as it is defined below.

What I seek to secure by United States Letters Patent is:

1. In a door operating apparatus in combination with a motive device, of a link for connecting the motive device with the object to be operated, the link comprising two relatively movable members, means for resisting relative movement of the members, a cam element attached to one of the members and engaging a cam surface formed on the other member and a control device operated by the cam element when the reaction on the motor through the link exceeds a predetermined value.

2. In a door operating apparatus in combination with a motive device, of a link for connecting the motive device with the object to be operated, the link comprising two relatively movable members, means for resisting relative movement of the members, a cam element attached to one of the members and engaging a cam surface formed on the other member and a control device operated by the cam element for reversing the motive device.

3. In testimony whereof I have hereunto set my hand on this 15th day of May A. D., 1930.

ROSCOE D. CONKLIN.
